UNITED STATES PATENT OFFICE

161,959

COMBINED COUNTER DESK AND SAFE

Frank C. Park, Marietta, Ohio, assignor to Remington Rand, Inc., New York, N. Y., a corporation of Delaware

Application November 27, 1948, Serial No. 149,852

Term of patent 14 years

(Cl. D33—7)

To all whom it may concern:

Be it known that I, Frank C. Park, a citizen of the United States, residing at Marietta, in the county of Washington and State of Ohio, have invented a new, original, and ornamental Design for a Combined Counter Desk and Safe, of which the following is a specification, reference being made to the accompanying drawings, forming a part thereof.

Fig. 1 is a perspective showing the new design looking at the front and left-hand end thereof;

Fig. 2 is a perspective on a smaller scale than Fig. 1 showing the new design looking at the rear and right-hand end thereof; and

Fig. 3 is an end elevation on a smaller scale than Fig. 1, looking at the left-hand end of the desk.

The invention claimed is:

The ornamental design for a combined counter desk and safe, as shown.

FRANK C. PARK.
